UNITED STATES PATENT OFFICE.

ORRIN N. BRAINERD, OF ST. LOUIS, MISSOURI.

BOX-FASTENER.

SPECIFICATION forming part of Letters Patent No. 323,106, dated July 28, 1885.

Application filed November 4, 1884. (No model.)

To all whom it may concern:

Be it known that I, ORRIN N. BRAINERD, of the city of St. Louis, in the State of Missouri, have invented a certain new and useful Improvement in Box-Fastenings, of which the following is a full, clear, and exact description, reference being had to the accompanying drawings, forming part of this specification, and in which—

10 Figure 1 is a perspective view of an egg-box with my improved fastening applied, the lid being removed from the box. Figs. 2, 3, 4, and 5 are enlarged detail views of different parts. These figures will be more particularly mentioned in the body of the specification.

15 Referring to the drawings, A represents the box, B the lid, C cleats secured to the box, and D cleats secured to the lid, as usual. At one end of the box, secured to the cleat, is a

20 spring-hook, I, adapted to engage over the cleat on the corresponding end of the lid, as shown in Fig. 4. This cleat on the lid is preferably recessed at J, forming an inclined surface that causes the hook to be forced outward to engage over the cleat by simply pressing down on the lid. The upper edge of the cleat has a recess, L, to receive the end of the hook, or this recess may be made in the top just over the cleat, if desired. The lower part of the 25 hook is preferably strengthened by a strap, M, that fits outside of it, and through which the retaining - screw passes. The strap preferably passes or projects under the box-cleat, as shown in Fig. 4. By the use of this strap the hook is not liable to be broken where the screw passes through it. The lid-cleats and

the upper end of the hook may be perforated at N to receive a nail or pin, O, to hold the fastening securely in place when extraordinary care is needed. On the other end of the box is a 40 plate, P, with a hook on its upper end which projects outwardly and engages over the cleat on this end of the lid that has a recess, T, to receive it. The plate does not require to have any spring to it, as this end of the lid is put 45 on first and drawn over against the box, and then as the other end of the lid is lowered into place the hook of the plate enters the recess T. In taking off the cover the spring-hook is pulled back, this end of the lid raised, and 50 then the lid moved bodily away from the hooked plate P.

I claim as my invention—

1. In combination with the box A, having the cleat C, and the spring I, having its extremity bent at right angles, as described, the 55 cover B, the cleat D, secured thereto, the chamfered notch J, cut in said cleat, and a recess or mortise, L, for the réception of the end of the spring I, as set forth.

2. In combination with the box A, having the cleat C, and the spring I, having its extremity bent at right angles and perforated, as described, the lid B, having the cleat D, the 65 chamfered notch J, cut in the side of said cleat D, the mortise L, cut in the top thereof, the perforations N, and the pin O, as and for the purposes set forth.

ORRIN N. BRAINERD.

In presence of—

GEO. H. KNIGHT,
SAML. KNIGHT.
